(57)

CLAIM

The ornamental design for a gaming desk, as shown and described.

DESCRIPTION

FIG. 1 is a perspective view of a gaming desk showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a bottom perspective view of FIG. 1;

FIG. 9 is an enlarged detailed view of the encircled area 9 in FIG. 5;

FIG. 10 is an enlarged detailed view of the encircled area 10 in FIG. 7; and,

FIG. 11 is an enlarged detailed view of the encircled area 11 in FIG. 8.

The broken line portion of the figure drawings is included to show portions of the article that forms no part of the claimed design.
